UNITED STATES PATENT OFFICE.

ALPHONSUS FIEN, OF NEW YORK, N. Y., ASSIGNOR TO S. H. POMEROY COMPANY, INC.,
OF NEW YORK, N. Y., A CORPORATION OF NEW YORK.

METAL WINDOW.

Application filed April 21, 1925. Serial No. 24,747.

To all whom it may concern:

Be it known that I, ALPHONSUS FIEN, a citizen of the United States, residing in the borough of Bronx, city and State of New York, have invented certain new and useful Improvements in Metal Windows, of which the following is a specification, reference being had to the accompanying drawings, forming a part hereof.

This invention relates to the construction of window frames formed of sheet metal and is particularly concerned with the construction at the corners, where the jambs, or vertical members, and the head or lintel and sill, or horizontal members, meet. The objects of the invention are to reduce the cost of manufacture, to attain greater strength at the points of union of the vertical members and the horizontal members, and to improve the appearance. In accordance with the invention one of the members is formed at its end with tongues which are made to interlock with the adjacent portions of the other member, as by being bent over upon the edge of the other member or passed through slots in the other member, or in both ways, a strong union of the two members being secured in this manner without the use of rivets and at greater reduced expense in labor. The effect, in appearance, of a mitered joint is secured by forming in the face of one member a diagonal slot and passing through it a broad tongue formed at the end of the corresponding face of the other member. The frame is stiffened, at the corner, by a brace which is so constructed as to form also a housing or support for the sash pulleys. The invention will be more fully explained hereinafter with reference to the accompanying drawings in which it is illustrated and in which—

Figure 1 is a view in vertical sectional elevation, on the plane indicated by the broken line 1—1 of Figure 2, of the corner portion of a window frame constructed in accordance with the invention, one of the interlocking tongues being shown in the position which it has before it is turned over and smashed down.

Figure 2 is a view of the same as seen in elevation from the right hand in Figure 1, the head or lintel being shown in section on the plane indicated by the broken line 2—2 of Figure 1.

Figure 3 is a view in elevation of the separated end portions of two members of the frame, with the interlocking tongues in the positions which they have before the two members are assembled and the tongues smashed down.

Figure 4 is a view in elevation showing the two members assembled, with the interlocking tongues at one point partly smashed down.

Figures 5 and 6 are detail views illustrating particularly the housing or support for the sash pulleys, Figure 6 being a view in section on the plane indicated by the broken line 6—6 of Figure 5.

Figures 7, 8 and 9 are detail views showing successive steps in the interlocking of the members.

Figure 10 is a view on line 10—10 of Figure 2, looking to the right.

Figures 11, 12 and 13 are vertical sectional views on lines 11—11, 12—12, and 13—13, respectively, of Figure 10, and

Figure 14 is a view in elevation of the corner construction from the outside looking to the left of Figure 3.

The form of window frame in connection with which the present improvements have been developed is that in which the vertical frame member or jamb *a* is of sheet metal bent to form an enclosed weight box, having at its face a separable portion *b* which forms guideways and a parting strip for the sashes and is held in place removably by screws *b'* which engage braces *c* and *d* of heavier material located within the weight box. The brace *d*, at the corner, which forms the supporter housing for the sash pulleys as hereinafter described, is preferably secured to the main portion of the jamb by screws *d'* passed through the face of the jamb.

The horizontal member, shown here as the head or lintel *e*, is also of sheet metal bent to the desired form, which may or may not be completely enclosed.

The end portions of the frame members *a* and *e* each extends in full width to the edge of the other member, the end portion of the lintel member *e*, in the construction shown, terminating on a line at right angles to its upper edge and, when assembled, abutting against the back wall *a'* of the side member, and the end portion of the side member extending to the upper edge of the

lintel member and having tabs, as herein-after described, extending beyond this upper edge until folded down as hereinafter described.

- 5 In the exposed side of one of the frame members as of the head or lintel member *e*, is formed a diagonal slot *e'* extending from the corner *g* at which the lower horizontal face of the lintel member meets the inner 10 vertical face of the side member *a*, towards, but not to, the outer corner *g'* at which the outer vertical face of the side member *a* meets the upper edge of the lintel member. This slot terminates at such distance from 15 this corner as to leave a strip of sheet metal between it and the end of the member *e*, of substantial width, as shown in Figures 1, 3, 4, 10 and 14. Through this slot *e'* is passed, from the outside, the tongue *a'* 20 which is formed on the end portion of the side member *a* by deep cut or cleft *h* extending inward from the end of the end portion to a point *g''* so as to leave to the left of this cut or cleft *h*, as shown in Figure 25 14, a tab *g''*, relatively long, extending upward beyond the line of the upper edge of member *e* until it is folded down as hereinafter described. Tongue *a'* thus formed is of less width than the member *a* and is 30 adapted to fit the diagonal slot *e'*. This tongue *a'* is provided on its end with a tab or tabs, here shown as two in number, *h'* and *h''*, extending upward a relatively short distance.
- 35 The lintel member *e* is provided along its upper edge with one or more, preferably two as shown, tabs *e''*, relatively long, extending upward in position to be folded over the relatively short tabs *h'* and *h''* on 40 the end of tongue *a'* of the side member, and has also, at its end a tab *h''*, relatively short and of a width corresponding with the width of tab *g''* on the end of member *a*.
- When the members *a* and *e* are assembled 45 by passing tongue *a'* through slot *e'* the tab *g''* will extend upward, to the right in Figure 14, above the upper edge of member *e*, on the outside of the outer end portion of member *e* and the relatively short tab *h''* 50 will lie against the inner face of this tab *g''*. The relatively short tabs *h'* and *h''* on the end of tongue *a'* will lie against the inner faces of tabs *e''* on the upper edge of member *e*. The lower or base portion of tongue 55 *a'* will be on the outside and the upper or terminal portion will be on the inside, of the member *e*.

The members *a* and *e* being thus assembled, the end of tab *g''* is folded over 60 onto tab *h''* and the ends of tabs *e''* are folded over onto tabs *h'* and *h''*. Tabs *g''* and *h''* are then folded inward on the line of the upper edge of member *e* and are compressed or smashed against the inner face of the end 65 of member *e* thus interlocking the tabs to-

gether as is done in double seaming. Tabs *e''* enclosing tabs *h'* and *h''* are then folded inward in the same way and are compressed or smashed against the inner face of the end portion of tongue *a'*. By this double seaming together of the tabs the end portions of members *a* and *e* are so locked together that there can be no movement of one on the other and, at the same time the end portion of the tongue *a'* is held so closely against the member *e* that no moisture can enter between them. If desired the end portions of the members *a* and *e* may be secured together by spot welding.

The effect to the eye, of the construction described is that of a mitre joint as shown in Figure 14.

The back wall *a''* of the frame member *a* may also be formed, if desired, with a tab *a''* which may be utilized in securing the top or cover, not shown, of the head or lintel *e*.

The opposite side *a''* of the frame member *a* is also carried above the finished top line of the frame member *e* to form a tab or tabs *a''* which, in like manner as previously described, and as shown in the right hand in Figures 7, 8 and 9, are each folded over upon a relatively short tongue *e''*, extended above the upper finish line of the member *e* so as to enclose it, and, with the relatively short tab thus enclosed, is again bent or folded inward against the inner face of the member *e* to thus form a double seam or interlocked joint extended above the upper finish line of the member *e* and are bent or lapped over upon and with the same and hammered or smashed, as shown in Figure 9, to make a firm union at the side.

In the construction shown the vertical and horizontal members are each formed of a single strip of relatively thin sheet metal bent longitudinally to form inner and outer face portions and a central portion connecting the face portions. In the vertical member *a* the central portion forms the back wall *a''* connecting the outer edges of the face portions and between the inner edges of the face portions, that is the edges adjacent to the window sash, is the opening in which is secured the separable portion *b*. In the horizontal member *e*, on the other hand, the central portion between the inner and outer face portions extends between the inner edges of these face portions, that is the edges adjacent to the window sash.

The horizontal or lintel member *e* is formed, on the face portion opposite that on which is formed the corner construction above described, with a rabbet *e''* and the vertical member *a* is provided with a similar rabbet *a''* the upper end of which fits within the end of the horizontal rabbet *e''*, the outer or rear wall *a''* closing the end of this rabbet. The face of rabbet *e''* is cut at an angle, as shown at *a''* to give the appearance of a

mitre joint. The outer, or upper, wall of rabbet e^6 is provided at its end with an upturned, relatively short tab e^8 and, at a point opposite the inner wall of rabbet a^{10} , is provided with a transverse slot e^7 . The outer, or rear, wall of rabbet a^{10} is provided at its end with a relatively long tab a^8 of such length as to permit its end portion to be folded over onto the relatively short tab e^8

10 so as to enclose it. After it is thus folded over onto tab e^8 the two tabs are together, folded over onto the upper wall of rabbet e^6 .

The inner wall of rabbet a^{10} is provided at its end with a tongue a^7 adapted to be passed 15 through the transverse slot e^7 and of such length that when passed through the slot and bent down against the upper wall of rabbet e^6 it will extend to the base of tab e^8 and will be caught and held down by the interlocked tabs a^8 and e^8 . The rabbets e^6 and a^{10} are thus firmly locked together.

The brace d , above referred to, not only serves to stiffen the member a at the corners and to form a support for the under side of the head or lintel e by means of an ear e^9 formed integral with the under side of the head or lintel from which it is bent downward at right angles and secured to brace d by a screw e^{10} , but it serves also as a support 25 and housing for the sash pulleys. As shown, the brace d is carried well above the level of under side of the head or lintel e and is bent, as at d^2 , to form a seat for the reception of the inner ends of the two spindles f upon 30 which are mounted the sash pulleys f' . The two spindles, independent of each other to facilitate replacement in case of necessity, are clamped in the head d' by a plate d^3 which is indented, as at d^4 , to hold the spindles apart and permit longitudinal movement when the plate d^3 is removed, the plate d^3 being secured to the plate d by a screw d^5 which is passed through the indented portion 35 of the plate d^3 and is threaded into the indented portion d^2 of the plate d . Should it be necessary at any time to renew either sash pulley or its spindles, the face plate b of the jamb is removed, the screws d' and e^{10} are withdrawn and the brace is lowered within 40 the jamb sufficiently to permit the screw d^4 to be withdrawn and the spindles released for substitution or adjustment or repair.

It will be understood that various changes 55 can be made in details of construction and arrangement and that the invention, except as pointed out in the claims, is not restricted to the particular construction shown and described herein.

I claim as my invention:

60 1. In a corner construction for sheet metal window frames, the combination of a vertical frame member and a horizontal frame member the end portion of each extending across the other, the end portion of one member having a diagonal slot formed therein

terminating short of its upper edge and the end portion of the other member having a tongue formed therein of a width less than that of the end portion and extending through said diagonal slot so that a part of 70 said tongue lies against the outside and a part against the inside of the slotted member, and means for securing together the end portions of the two members.

2. In a corner construction for sheet metal 75 window frames, the combination of a vertical frame member and a horizontal frame member the end portion of each extending across the other, the end portion of one member having a diagonal slot formed therein 80 terminating short of its upper edge and the end portion of the other member having a tongue formed therein of a width less than the width of the end portion and extending through said slot from the outside so that the base of the tongue lies against the outside and the end portion of the tongue lies against the inside of the slotted member, and means for securing the end portion of the tongue to the slotted member.

3. In a corner construction for sheet metal 85 window frames, the combination of a vertical frame member and a horizontal frame member the end portion of one member extending across the end portion of the other member, the end portion of one member having a diagonal slot formed therein 90 terminating short of its upper edge and the end portion of the other member having a tongue formed therein of a width less than that of the end portion and extending through said slot so that a part of said tongue lies against the outside and a part against the inside of the slotted member, and means for securing together the end portions of the two members comprising a relatively short tab on the end of the tongue and a relatively long tab on the slotted member interlocked with the short tab on the tongue to form a double 95 seam joint.

4. In a corner construction for sheet metal 100 window frames, the combination of a vertical frame member and a horizontal frame member the end portion of each extending across the other, the end portion of one member having a diagonal slot formed therein 105 terminating short of its upper edge and the end portion of the other member having formed therein a tongue of a width less than that of the end portion and a tab extending beyond the line of the end of the tongue and separated from the tongue by a cleft, the tongue extending through said slot from the outside so that the base portion of the tongue 110 lies against the outside and the end portion lies against the inside of the slotted member and the tab lies against the outside of said slotted member, and means for securing together the end portions of the two members comprising a tab on the slotted mem- 115

120

125

130

ber opposite the tab on the other member the two tabs being interlocked to form a double seam joint.

5. In a corner construction for sheet metal window frames, the combination of a vertical frame member and a horizontal frame member each of said frame members having a rabbet formed on one of its faces the outer wall of one of the rabbets extending across 10 and closing the end of the other the outer walls of both rabbets being each provided at at its end with a tab the tab of one rabbet being interlocked with the tab of the other to form a double seam joint at the meeting 15 ends of said outer walls.

6. In a corner construction for sheet metal window frames, the combination of a vertical frame member and a horizontal frame member each of said frame members having 20 a rabbet formed on one of its faces the outer wall of one of the rabbets extending across and closing the end of the other and having a tongue formed on its inner wall, the outer wall of the other rabbet being provided with 25 a transverse slot adapted to permit said tongue to pass through it, said tongue being bent down into contact with the wall in which said slot is formed.

7. In a corner construction for sheet metal window frames, the combination of a vertical frame member and a horizontal frame member each of said frame members having a rabbet formed on one of its faces the outer wall of one of said rabbets extending across 30 and closing the end of the other rabbet, having a relatively long tab on the end of its outer wall and a relatively long tongue on the end of its inner wall, the outer wall of the other rabbet having a relatively short 35 tab on its end and a transverse slot opposite the inner wall of the first mentioned rabbet adapted to permit said tongue to pass through it, the tongue being bent down into contact with the wall in which the slot is formed, and the tabs being interlocked one with the other.

8. In a corner construction for sheet metal window frames, the combination of a vertical frame member and a horizontal frame 50 member each of said frame members having a rabbet formed on one of its faces the outer wall of one of said rabbets extending across and closing the end of the other rabbet, having a relatively long tab on the end of its

outer wall and a tongue on the end of its 55 inner wall of a length corresponding to the width of the other rabbet, the outer wall of the other rabbet having a relatively short tab on its end and a transverse slot opposite the inner wall of the first mentioned rabbet 60 adapted to permit said tongue to pass through it, said tongue being bent down into contact with the wall in which the slot is formed and extending towards the end of 65 said wall carrying the relatively short tab, the tabs on the ends of the outer walls of the rabbets being interlocked one with the other and bent down onto the end of said tongue.

9. In a sheet metal window frame, the combination of a vertical frame member and a horizontal frame member each comprising an inner and outer face portion and a central portion continuous with the face portions the central portion of the horizontal 70 member extending between the inner edges of its face portions and the central portion of the vertical member extending between the outer edges of its face portions, a heavy 75 metal brace secured within the vertical frame member near its upper end, and an ear continuous with the central portion of the horizontal member and bent into parallelism with said brace and secured thereto.

10. In a sheet metal window frame, the combination of a vertical frame member, a heavy metal brace secured therein at its upper end and extended above the same and indented, a spindle seated in the indented portion of the brace, a sash pulley mounted on the spindle, a plate, and means to secure the plate to the brace to clamp the spindle 90 in its seat.

11. In a sheet metal window frame, the combination of a vertical frame member, a heavy metal brace secured therein at its upper end and extended above the same and indented horizontally, spindles seated in said indentation, sash pulleys mounted on the spindles, a plate having an indented portion 95 to enter the indented portion of the brace between the ends of the two spindles, and means to secure the plate to the brace to secure the spindles in the indented portion of the brace.

This specification signed this 6th day of April, A. D. 1925.

ALPHONSUS FIEN.
